UNITED STATES PATENT OFFICE

167,363

MICROPHOTOGRAPH VIEWER

Edward O. Peters, La Crosse, Wis.

Application September 15, 1951, Serial No. 16,651

Term of patent 14 years

(Cl. D61—1)

To all whom it may concern:

Be it known that I, Edward O. Peters, a displaced person of Latvian origin, and a resident of the city of La Crosse, county of La Crosse, State of Wisconsin, have invented a new, original, and ornamental Design for Microphotograph Viewer, of which the following is a specification, reference being had to the accompanying drawing forming a part thereof in which:

Figure 1 is a perspective view of a microphotograph viewer illustrating my new design,

Figure 2 is a side elevation view of the microphotograph viewer shown in Figure 1,

Figure 3 is an elevation view of the front of the microphotograph viewer shown in Figure 1, and

Figure 4 is an elevation view of the back of the microphotograph viewer shown in Figure 1.

I claim:

The ornamental design for a microphotograph viewer, substantially as shown.

EDWARD O. PETERS.
